UNITED STATES PATENT OFFICE.

WILLIS E. FINCH AND WALTER F. STIMPSON, OF LOUISVILLE, KENTUCKY; SAID FINCH ASSIGNOR TO SAID STIMPSON.

SCALE.

Application filed November 7, 1921. Serial No. 513,227.

The invention relates to scales and more particularly to that type known as "counter scales", and the invention consists in various features of the construction as hereinafter set forth.

In the drawings:—

Figure 1 is a vertical central section through the scale;

Figure 2 is a plan view with the platform and a portion of the housing removed and the column shown in horizontal section;

Figure 3 is a vertical cross section through the column;

Figure 4 is a front elevation;

Figure 5 is a plan view;

Figure 6 is an enlarged section of a portion of Fig. 1;

Figure 7 is a cross-section through the housing; and

Figure 8 is a detail of the finger N⁵ showing the method of adjustment.

As specifically constructed, A is the platform supporting lever, preferably a lever of the third class having the wide portion A' to which the fulcrum pivots B are attached, the rearwardly extending arms A² carrying the platform supporting pivots and the central rearwardly extending arm A³ which connects with the steelyard rod. C is the lower frame and housing member which surrounds the platform lever and which corresponds to the shape thereof. Thus at the front the housing member C is of a width to receive the portion A' of the platform lever, including the rearward extensions A². At the center the member C is reduced in width, as indicated at C', merely providing a housing for the rearward extending portion A³ of the lever and at the rear the casing is enlarged at C² to form a support for the column. D is a complementary housing member arranged above the platform lever, being apertured at D' for the passage of the supporting legs E of the platform supporting frame E'. When the complementary portions C and D of the housing are placed together, they will completely enclose the platform lever. The lower section is raised by feet F and therefore the space beneath the frame and above the counter is easily accessible for cleaning.

G is the hollow column which is supported upon the portion C² of the base and which at its upper end is laterally extended at G' to support the cylinder housing H. The

column G encloses the steelyard rod I as well as the dash-pot and other accessories and it is preferably made with transparent panels G², front and rear, through which the enclosed mechanism may be inspected. 60

Within the cylindrical casing H is the weighing and computing cylinder M, this being mounted upon a shaft M' journaled in anti-friction bearings at opposite ends of the casing H. The shaft M' has mounted thereon centrally thereof the pinion M² which engages a rack N pendant from the upper end of the rod I⁵. The lower end of the rack has a rearwardly extending loop-shaped weight member N' which embraces the rod I⁵ and serves to yieldably press the rack against the pinion. Thus the movement of the platform lever, which is transmitted by the steelyard rod, will effect a movement of the rack and a rotation of the 70 pinion and cylinder M.

The platform supporting frame E' carries the weighing platform O, this being preferably a glass plate. To hold the platform from tipping, a check rod is provided, this being connected to the rear end of the platform frame and rising vertically therefrom in front of the column G. The upper end of this rod P enters the cylindrical housing H between sections of the computing cylinder M and at the upper end of the rod P is the rearwardly-extending portion P' to which is attached the fitting P² for engaging the forwardly-extending check link P³. The forward end of this link is 80 attached by a fitting P⁴ to a bifurcated segmental bracket arm Q mounted on the column and extending between the cylinders M. Thus the check rod extends upward to nearly the center of the cylinder and by its relatively great length lessens the amount of frictional and lateral oscillation due to the movement of the platform. 85

To hold the rack N from accidental disengagement from the pinion, a finger N⁵ is arranged to extend in rear of the rack and pinion and between the former and the rod I⁵. This finger is preferably mounted on an inwardly extending portion Q' of the bracket arm Q and to permit of proper adjustment the finger has a rocker bearing N² for engaging the member Q' and a pair of attachment screws N³ and N⁴ on opposite sides thereof. Thus by alternately loosening and tightening the screws N³ and N⁴, 100 105 110

the finger may be rocked upon its rocker bearing so as to adjust it towards or from the rack bar and the adjustment is such that the finger will normally be out of contact with the rack bar and will only serve to prevent disengagement of the rack teeth from the pinion.

The platform lever A is fulcrumed in a yoke member R which is mounted on lugs R¹, rising from the lower casing member C. R² are upward extensions of the member R at opposite ends thereof, which carry the bearings for the knife-edged fulcrum pivots. R³ are upward extensions from the central portion of the member R which embrace the cross bars A⁴ of the lever A and support above the same the plate R⁴. On this plate R⁴ is arranged a level member R⁵ which is preferably circular in form and engages an aperture in the upper portion D of the level housing, so that the level will be visible from above said housing. The level member R⁵ has the usual transversely arranged level tubes and these are visible through the transparent platform and through an aperture E² in the platform supporting frame. The scale is leveled by a vertical adjustment of the feet F which are provided with threaded stems that may be raised or lowered by turning.

To support the scale without rocking, a three-point bearing is desirable, but this does not afford as great stability as where four points are used. We have provided a four-point support by placing the legs F under opposite sides of the wide portion of the housing C and two legs beneath the column G. These latter supports are, however, connected to an evener lever S which is centrally fulcrumed within the base of the column, as indicated as S, thereby forming in effect a three-point support. However, stability is obtained by limiting the independent movement of the legs F, which are attached to the lever S, so that a slight tipping of the scale will take up the lost motion and prevent further tipping.

It is usual to provide spring scales with a thermostatically controlled adjustment means for compensating for temperature changes. We have provided a construction of thermostatic control that is effective in its operation and easily applied to the scale. This consists in a thermostat T of the expansible chamber type, which is located between the cross bars A⁴ of the platform lever A. As shown, the thermostat comprises a series of axially aligned chambers formed of thin metal which are filled with an expansible fluid and hermetically sealed. The forward end of this thermostat is rigidly attached to the lever, while the rear end is coupled to a rod T' passing rearward to a channel in the portion A³ of the lever. The rod T' is attached to an anti-friction car-

riage T² which has the pivot T³ connecting with the steelyard rod. Therefore, whenever there is a rise in temperature, there will be a corresponding expansion of the thermostat T, which will carry the pivot T³ 70 rearward, increasing the leverage of the arm A³. On the other hand, a drop in temperature will contract the thermostat T and will decrease the length of the lever arm A³.

For setting the cylinder to the zero point 75 when the platform is without load, provision is made for raising and lowering the yoke K, which anchors the weighing springs J. This consists of a pair of rods U arranged on opposite sides of the springs J and extending from the yoke K downward into the base. The lower ends of these rods rest upon a bifurcated rocker member V which has a downwardly extending arm V' adjacent to the end of a rod V² which passes centrally beneath the housing member C to the forward end thereof. The rear end of the rod V² is threaded and engages a threaded aperture in a lug V³, while the forward end is swiveled in a lug V⁴ and is slotted to be 80 turned by a screw-driver. The turning of the rod V² in one direction will move it rearward and by engaging the arm V' will tilt the rocker V and raise the rods U. A rotation of the rod V² in the opposite direction will produce the opposite effect and the lowering of the rods U. The movement of the rods U will raise or lower the yoke K and springs J, thereby effecting an adjustment of the cylinder M. 85

Variation in temperature will not only vary the tension of the weighing springs, but will also effect the adjustment of the indicator. This is compensated for by forming the rods U of a metal such as brass, which, by its differential coefficient of expansion, will act as a thermostat. The fact that the rods U extend from the base to the cylinder housing gives a sufficient length to produce the compensation without the use of 105 levers or other complications and this greatly simplifies the construction.

What we claim as our invention is:—

1. In a scale, the combination with a hollow base, of a platform supporting lever within said base, a column rising from said base, a spring within said column connected to said lever, a vertically adjustable anchor for said spring, an arm connected to said anchor, a rockable member within said base 115 for actuating said arm to adjust said anchor, a rod in said column engaging said anchor at one end and extending downward through said column into said base for engaging said rockable member, and a rod extending to 120 the forward end of said base for operating said rockable member.

2. In a scale, the combination with a hollow base, of a platform lever within said base, a hollow column extending upward 130

- from said base, a weighing spring within said column connected to said lever, an anchor for said weighing spring, and an adjusting mechanism for said anchor comprising a pair of rods within said column on which said anchor is supported, a bell crank lever for supporting the lower end of said rods, and means operable from outside said base for adjusting said bell crank lever.
5. In a scale, the combination with a base, of a platform supporting lever thereon, a housing column extending upward from said base, a weighing spring within said hollow column and connected to said lever, an anchor for said weighing spring and an adjusting mechanism for said anchor comprising a pair of rods on opposite sides of said weighing spring and lever on which said anchor is supported, a rockable member for supporting the lower ends of said rods, means operable from outside said base for adjusting said rockable member to raise or lower said rods, said rods having a coefficient of expansion differing from that of said column to automatically compensate for temperature changes.
10. 3. In a scale, the combination with a base, of a platform supporting lever thereon, a hollow column extending upward from said base, a weighing spring within said hollow column, an anchor for said weighing spring, a rod extending from said base to said anchor for vertically adjusting the same, said rod having a coefficient of expansion differing from that of said column to automatically compensate for temperature changes.
15. 4. In a scale, the combination with a base, of a platform supporting lever thereon, a hollow column extending upward from said base, a weighing spring within said hollow column, an anchor for said weighing spring, a rod extending from said base to said anchor for vertically adjusting the same, said rod having a coefficient of expansion differing from that of said column to automatically compensate for temperature changes.
20. 5. In a scale, the combination with a base, of a platform lever supported thereon, a hollow column extending upward from said base, a steelyard rod connected to said lever and extending upward within said hollow column, said steelyard rod comprising a pair of connected parallel bars having laterally offset portions and hollow portions above said lateral offset, a pair of weighing springs extending within said hollow portions and connected to said bars, and a dash-pot connected to said steelyard rod for retarding the movement thereof arranged within the laterally offset portion.
25. 6. In a scale, the combination with a base, of a platform lever supported thereon, a hollow column extending upward from said base, a steelyard rod connected to said lever and extending upward within said hollow column, said steelyard rod comprising a pair of connected parallel bars having laterally offset portions and hollow portions above said lateral offset, a pair of weighing springs extending within said hollow portions and connected to said bars, a dash-pot secured to said column and arranged within the laterally offset portion a piston within said dash-pot connected to said steelyard rod an anchor for the upper ends of said springs, and adjustment means for said anchor comprising a pair of rods on opposite sides of said parallel bars and dash-pot, and means located on said base for vertically adjusting said rods.
30. 7. In a scale, the combination with a base, of a platform lever supported thereon, a hollow column extending upward from said base, a steelyard rod connected to said lever and extending upward within said hollow column, a weighing spring within said column connected to said steelyard rod, an anchor for said weighing spring, an adjusting means for said anchor comprising a pair of rods on opposite sides of said spring and steelyard rod having their upper ends engaging said anchor, and means on said base engaging the lower ends of said rods for vertically adjusting the same.
35. 8. In a scale, the combination with a base, of a platform lever supported thereon, a hollow column extending upward from said base, a steelyard rod connected to said lever and extending upward within said hollow column, a weighing spring connected to said steelyard rod, a yoke forming an anchor for the upper end of said spring, a pair of rods on opposite sides of said steelyard rod and spring having their upper ends engaging said yoke, and an adjustable member for supporting the lower ends of said rods, comprising a rocker having laterally extending arms for engaging said rods, a vertically ex-
- tending arm, and an adjustable member for engaging said vertically extending arm operable from outside said hollow base.
40. 9. In a scale, the combination with a base, of a platform lever supported thereon, a hollow column extending upward from said base, a steelyard rod connected to said lever and extending upward within said hollow column, said steelyard rod comprising a pair of connected parallel bars having laterally offset portions and hollow portions above said lateral offset, a pair of weighing springs extending within said hollow portions and connected to said bars, a dash-pot secured to said column and arranged within the laterally offset portion a piston within said dash-pot connected to said steelyard rod an anchor for the upper ends of said springs, and adjustment means for said anchor comprising a pair of rods on opposite sides of said parallel bars and dash-pot, and means located on said base for vertically adjusting said rods.
45. 10. In a scale, the combination with a base and a platform lever supported thereon, of a hollow column rising from said base, a cylinder housing at the upper end of said hollow column, a bifurcated cylinder journaled within said cylinder housing, a pinion for said cylinder between the furcations thereof, a steelyard rod connected to said lever and extending upward within said hollow column, a weighing spring connected to said steelyard rod, a rod connected to said steelyard rod and extending upward beyond said weighing spring and pinion, a rack pivotally attached to the upper end of said rod and depending therefrom, said rack intermeshing with said pinion, and a loop-shaped weight arm extending rearward from said rack embracing said rod and serving

to hold said rack in engagement with said pinion.

11. In a scale, the combination with a base, of a platform lever supported thereon, 5 a hollow column rising from said base, a cylinder housing at the upper end of said hollow column, a bifurcated cylinder within said cylinder housing, a shaft on which said bifurcated cylinder is mounted, a pinion on 10 said shaft between the furcations of said cylinder, a steelyard rod connected to said lever and extending upward within said column, said steelyard rod comprising a pair of spaced and cross-connected parallel 15 bars, a pair of weighing springs aligned with portions of said parallel bars and connected thereto, a rod extending upward from said steelyard rod and arranged centrally between the bars thereof, said rod passing upward beyond and in rear of said pinion, a 20 forward extension at the upper end of said rod, a rack pivoted to said forward extension and depending therefrom, said rack being in mesh with said pinion, and a loop-shaped weight arm at the lower end of said 25 rack extending rearward therefrom and embracing said rod.

12. In a scale, the combination with a base, of a platform lever supported thereon, 30 a platform supporting frame resting upon said platform lever, a hollow column rising from said base, a cylinder housing at the upper end of said hollow column, a bifurcated cylinder within said cylinder housing, 35 a shaft on which said bifurcated cylinder is mounted, a pinion on said shaft between the furcations of said cylinder, a steelyard rod connected to said lever and extending upward within said hollow column, a weighing spring connected to said steelyard rod, a rod extending upward from said steelyard rod above said pinion and in rear thereof, a rack pivotally attached to the upper end of said rod and depending therefrom, being in mesh with said pinion, a 40 check rod extending upward from said platform supporting frame and into said cylinder housing; a check link connected to the upper end of said check rod within said 45 cylinder housing, a bracket arm mounted on said hollow column extending upward therefrom and forming an anchor for said check link, and a finger extending from said bracket arm in rear of said rack forming a 50 stop for preventing disengagement of said rack from said pinion.

13. In a scale, the combination with a cylinder and a pinion for operating the same, of a rack engaging said pinion, a rod 60 extending parallel to said rack and pivotally attached to the upper end thereof, a laterally extending weight arm at the lower end of said rack for yieldably holding the same in engagement with said pinion, and a finger extending between said rack and

rod forming a stop for holding the former from disengagement from its pinion.

14. In a scale, the combination with a frame, a cylinder supported thereon and a pinion for rotating said cylinder, of a rack 70 for engaging said pinion, a rod for actuating said rack pivotally attached to the upper end thereof, a laterally extending weight arm at the lower end of said rack for yieldably holding the same in engagement with 75 said pinion, a bracket rigidly mounted on said frame, a finger extending from said bracket between said rack and actuating rod, a rocker bearing on said finger for engaging 80 said bracket, and a pair of adjusting members for securing said finger to said bracket on opposite sides of said rocker bearing, whereby relative adjustment of said securing members will alter the position of said finger relative to said rack. 85

15. In a scale, a platform supporting lever having a wide open frame portion for supporting the platform and engaging the fulcrum and a central arm extending to the steelyard rod, spaced bars extending 90 across said open frame portion on opposite sides of said central arm, an expansible chamber thermostat located between said spaced bars having its forward end secured to said lever, a rod extending from the free 95 end of said expansible chamber parallel to said central arm, and an adjustable steelyard rod pivot on said arm connected to the outer end of said rod.

16. In a scale, a platform supporting lever comprising an open frame portion having fulcrum pivots and platform supporting pivots on opposite sides thereof and a hollow central arm extending to the steelyard rod, bars extending longitudinally across 100 said open frame on opposite sides of said central arm, an expansible chamber thermostat within the space between said bars having one end thereof attached to said lever, a rod secured to the free end of said thermostat and extending within said hollow arm, and a pivot for the steelyard rod 105 connected to the outer end of said rod and adjustably engaging said arms. 110

17. In a scale, the combination with the platform supporting lever, of a steelyard rod connected thereto, a rotary cylinder, a pinion for rotating said cylinder, a rack for engaging said pinion, an extension of 115 said steelyard rod above the center of said cylinder pivotally engaging the upper end of said rack and a weight member at the lower end of said rack extending laterally of the same whereby the rod is yieldingly held in engagement with said pinion. 120

18. In a scale, the combination with a base, a hollow column extending upward from said base, a cylinder at the upper end of said column, a platform supporting lever mounted on said base, a steelyard rod con- 125

nected to said platform lever and extending upward in said hollow column, a weighing spring within said hollow column engaging said steelyard rod, a cylinder mounted within said cylinder housing, a pinion for rotating said cylinder, a rack for engaging said pinion, an extension of said steelyard rod above said pinion pivotally engaging the upper end of said rack and a loop-shaped weight member at the lower end of said rack embracing the extension of said steelyard rod.

19. In a scale, the combination with a platform supporting lever, of a steelyard rod connected thereto, a rotary cylinder, a pinion for rotating said cylinder, a rack for engaging said pinion, an extension of said steelyard rod above the center of said cylinder pivotally engaging the upper end of said rack, means for yieldingly holding said rack in engagement with said pinion, and a

finger between said rack and the extension of said steelyard rod for preventing disengagement of said rack and pinion.

20. In a scale, the combination with a platform supporting lever, of a steelyard rod connected thereto, a rotary cylinder, a pinion for rotating said cylinder, a rack for engaging said pinion, an extension of said steelyard rod above the center of said cylinder pivotally engaging the upper end of said rack, means for yieldingly holding said rack in engagement with said pinion, a finger between said rack and the extension of said steelyard rod, a fulcrum for said finger and adjusting screws on opposite sides of said fulcrum for adjusting the position of said finger.

In testimony whereof affix our signatures.

WILLIS E. FINCH.
WALTER F. STIMPSON.
